H. M. WALKER

CHECK CONTROLLED MECHANISM

Filed Aug. 6, 1921

Patented July 31, 1923.

1,463,521

UNITED STATES PATENT OFFICE.

HARRY M. WALKER, OF GRAYBURG, TEXAS

CHECK-CONTROLLED MECHANISM.

Application filed August 6, 1921. Serial No. 490,238.

To all whom it may concern:

Be it known that I, HARRY M. WALKER, a citizen of the United States, residing at Grayburg, in the county of Hardin and State of Texas, have invented certain new and useful Improvements in Check-Controlled Mechanisms, of which the following is a specification, reference being had to the accompanying drawings.

10 This invention relates to check controlled mechanisms and has relation more particularly to a mechanism of this general character especially designed and adapted for use in connection with an endwise movable member, such as the operating rack for the piston comprised in a gasoline or kindred liquid vending machine, and it is an object of the invention to provide a mechanism of this general character having novel and improved means whereby said endwise movable member is normally held or locked against movement in a direction to effect a lift or delivery of the liquid.

Another object of the invention is to provide a mechanism of this general character embodying novel and improved means whereby an endwise movable member is normally held against movement in one direction and which means is rendered inactive under the influence of a suitable check, said means also including an element for holding the member against reverse movement when said means is in a position to permit the first named endwise movement of the member.

The invention consists in the details of construction and in the combination and arrangement of the several parts of my improved check controlled mechanism whereby certain important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

Figure 1 is a fragmentary view in elevation illustrating a mechanism constructed in accordance with an embodiment of my invention and in applied position;

55 Figure 2 is an enlarged fragmentary view partly in section and partly in elevation

illustrating my improved mechanism in detail;

Figure 3 is an enlarged fragmentary view of my improved mechanism illustrating certain of the parts in a second position;

Figure 4 is a sectional view taken substantially on the line 4-4 of Figure 3; and

Figure 5 is a detail sectional view taken substantially on the line 5-5 of Figure 3.

As disclosed in the accompanying drawings, 1 denotes the operating rack or member for the piston of a gasoline vending machine which extends upwardly within a housing H. The top 2 of the housing H is provided with a tubular depending sleeve or guide member 3 through which the upper portion of the rack or member 1 works during a delivery operation. The housing H is provided with a door 4 adapted to be locked in closed position, said door providing means whereby access may be had to the mechanism arranged within said housing H.

Extending inwardly and downwardly of the housing H is a chute 5, the lower end portion of which communicates with the inner end portion of a substantially horizontally disposed runway 6. The inner end of the runway 6 is open to provide communication with the collecting receptacle 7 supported within the housing H and which receives the checks ejected from the runway 6 as will hereinafter be explained.

The top wall of the chute 5 immediately adjacent the runway 6 is cut away, as at a, to facilitate the ejecting of the check C and the requisite coaction of said check with the holding means associated with the rack or holding member 1. The portion of the runway 6 immediately below the lower end of the chute 5 is of restricted diameter, as is particularly illustrated in Figure 5, so that the check when received therein is maintained in substantially a vertical position in order that said check may effectively perform the function desired.

Snugly working within this restricted portion of the runway 6 is a plunger 8 which is constantly maintained at the limit of its inward movement by an expandable member 9. This member 9, as herein disclosed, comprises a coil spring encircling the outwardly directed stem 10 carried by the plunger 8, said spring being interposed between the inner end of the plunger 8 and the cap 11 or the like closing the outer end of the runway 6. The stem 10 is of a length to extend

exteriorly of the housing and said extended end portion is provided with a knob 12 or the like to facilitate the desired manipulation of the plunger 8 and particularly to retract the same.

14 denotes a substantially V-shaped dog having its apex portion pivotally supported, as at 15, by a side wall of the housing H, the arms of said dog alternately engaging 10 the teeth 16 in the adjacent marginal portion of the rack or member 1, one of said arms serving to hold the rack or member 1 against endwise movement in one direction and the second arm serving to hold the rack 15 against endwise movement in the opposite direction. Extending outwardly from the pivoted or apex portion of the dog 14 is an arm 17.

Bearing against the outer end of the arm 20 17 is an end portion of an expansible spring 18, the opposite end of said spring bearing against a block 19 extending laterally from the lower part of the chute 5. This spring 18 as the arm 17 passes beyond the horizontal 25 center serves to maintain either of the arms of the dog 14 in proper engagement with the teeth 16 whereby the rack or member 1 is held against endwise movement in one direction yet free to move in the opposite direction 30 until the second arm of the dog 14 is engaged with the rack or member 1.

The outer end portion of the arm 17 rotatably supports at one side thereof a roller 20 which, when the lower arm of the dog 14 25 is engaged with the member or rack 1 to hold the same against upward movement, is positioned in close proximity to the inner end of the runway 6 and in the path of travel of the check C when within the runway 6 in advance of the plunger 8 so that as the check C is forced under the roller 20, the lower arm of the dog 14 will be freed from the rack or member 1 to permit the same to have upward endwise movement. During 40 this movement, the second or upper arm of the dog 14 is operatively engaged with the rack or member 1 to hold the same against reverse endwise movement. This position of the dog 14 is maintained by the spring 18 45 as the check C will contact with the roller 20 to cause the arm 17 to be swung upwardly beyond a horizontal center. As the check passes under the roller 20, it is received 50 within the receptacle 7.

55 Engaged with the rack or member 1 is a conventional gear or pinion 21 operated exteriorly of the housing H by the crank 22 or its equivalent. Extending from the dog 14 toward the rack or member 1 and substantially coplanar with the arm 17 is a spring arm 23. This arm 23 overlies a side 60 of the rack or member 1 and is in the path of travel of a pin 24 carried by the lower portion of the rack or member 1. As the 65 rack or member 1 moves upwardly, the pin

24 comes into contact with the spring arm 23 resulting in the upper arm of the dog 14 being disengaged from the rack or member 1 and the lower arm of said dog engaged with the rack or member 1 whereby said rack or member 1 is held against further upward movement or free to be moved in the reverse direction.

The pin 24 is adjustably engaged with the member or rack 1 through the longitudinally disposed slot 25. By adjusting the position of the pin 24 lengthwise of the member or rack 1, the length of the upward stroke of the rack or member 1 may be regulated as desired so that the quantity of gasoline or other liquid delivered during the upward movement of the rack or member 1 may be varied and particularly as may be necessitated by the cost or price of the gasoline or the like.

With a gasoline station or the like equipped with a mechanism constructed in accordance with an embodiment of my invention, the station may be operated upon the deposit of a coin of desired value within the chute 5 so that a customer can help himself without the assistance of an attendant and which is particularly desirable during the hours when it is not convenient for the owner to have his place of business open.

It is to be understood that after the check or coin C is deposited in the chute 5, the plunger 8 is moved by pull upon the stem 10 a distance sufficient to permit the check to drop in the runway 6 in advance of the plunger 8. The stem 10 is then released and the tension of the spring or member 9 is sufficient to force the check or coin C under the roller 20 and thereby operate the dog 14 to permit the rack or member 1 to be moved upwardly upon requisite operation of the operating member or crank 22.

When the dog 14 is moved into a neutral position or in a position with both of the arms free from the rack, the pump can be operated without the use of the check controlled mechanism.

From the foregoing description it is thought to be obvious that a check controlled mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a member supported for movement in opposite directions,

- a dog pivotally supported adjacent to said member and provided with two arms, one of said arms engaging the member to hold the same against movement in one direction 6 when the second arm is free of the member, the second arm engaging the member to hold the same against movement in the opposite direction when the first named arm is free of the member, check controlled 10 means for swinging the dog in one direction, a spring arm carried by the dog and extending toward the member, an element carried by the member and contacting with the arm of the dog upon movement of the 14 member in one direction for swinging the dog in one direction, and means for moving the member.
2. In combination with a member supported for endwise movement, a dog pivotally supported adjacent the member and provided with a pair of arms, one of said arms engaging the member when the other arm is free therefrom to hold the member against movement in one direction, the second arm engaging the member to hold the member against movement in the opposite direction when the first named arm is free therefrom, check controlled means for swinging the dog to engage one arm and disengage the second arm from the member, an additional arm carried by the dog and overlying the side of the member, an outstanding pin carried by the member and contacting with the last named arm of the dog upon predetermined movement of the member in one direction for swinging the dog to engage one arm and disengage the second arm from the member. 20
3. In combination with a member supported for endwise movement, a substantially V-shaped dog pivotally supported adjacent the member, one of the arms of the dog engaging the member when the other arm is free therefrom to hold the member against movement in one direction, a second arm engaging the member to hold the same against movement in the opposite direction when the first named arm is free therefrom, check controlled means for swinging the dog in one direction, co-acting means carried by the dog and the member for moving the dog in the opposite direction upon predetermined movement of the member, means co-acting with the dog 30
- for maintaining either of the arms of the dog in engagement with the member, and means for moving the member.
4. In combination with a member supported for endwise movement, a dog pivotally supported adjacent the member and provided with a pair of arms, one of said arms engaging the member when the other is free therefrom to hold the member against movement in one direction, a second arm engaging the member to hold the same against movement in the opposite direction when the first named arm is free therefrom, check controlled means for swinging the dog to engage one arm and disengage the second arm from the member, an additional arm carried by the dog and overlying the side of the member, an outstanding pin carried by the member and contacting with the last named arm of the dog upon predetermined movement of the member in one direction for swinging the dog to engage one arm and disengage the second arm from the member. 35
5. In combination with a member supported for endwise movement, a dog pivotally supported adjacent the member and provided with a pair of arms, one of said arms engaging the member when the other is free therefrom to hold the member against movement in one direction, a second arm engaging the member to hold the same against movement in the opposite direction when the first named arm is free therefrom, check controlled means for swinging the dog to engage one arm and disengage the second arm from the member, an additional arm carried by the dog and overlying the side of the member, an outstanding pin carried by the member and contacting with the last named arm of the dog upon predetermined movement of the member in one direction for swinging the dog to engage one arm and disengage the second arm from the member, and means for adjusting the pin lengthwise of the member. 40

In testimony whereof I hereunto affix my signature.

HARRY M. WALKER.
